UNITED STATES PATENT OFFICE.

OTTO HAENTJENS, OF HAZLETON, PENNSYLVANIA.

CENTRIFUGAL PUMP.

1,312,979.

Specification of Letters Patent. Patented Aug. 12, 1919.

Application filed April 24, 1919. Serial No. 292,363.

To all whom it may concern:

Be it known that I, OTTO HAENTJENS, a citizen of the German Republic, residing at Hazleton, in the county of Luzerne and State of Pennsylvania, and having a post-office address care of Barrett, Haentjens & Co., Hazleton, Pennsylvania, have invented certain new and useful Improvements in Centrifugal Pumps, of which the following

10 is a specification.

My invention relates to centrifugal pumps, and particularly to multi-stage pumps, the object of my invention being to provide a relatively low speed pump of efficient, simplified and improved construction. Among the features of improvement to which I may direct especial attention are, first, the arrangement of the pressure chamber in the foot of the pump casing, thus lessening the height and weight of the structure; second, the consequent lowered position of the axis of the driving shaft, which renders the structure compact and also reduces the weight; third, the novel shape of the passage connecting the pump stages and through which the water passes with a sharp change of direction but without material frictional losses. Other features of improvement will also appear in the accompanying drawings

30 in which—

Figure 1 is a vertical central section of a two-stage pump in which my invention is embodied;

Fig. 2 is a plan view of the lower half of the casing with the impeller and shaft removed;

Fig. 3 is a sectional elevation shown in line 3—3 of Fig. 1;

Fig. 4 is a diagrammatic scheme of a passage connecting the two stages of the pump;

Fig. 5 is a plan view of a three-stage pump in which my invention is embodied; and

Fig. 6 is an end elevation thereof showing the pressure chamber in section; and

Fig. 7 is a section on the line 7—7 of Fig. 6.

In certain particulars the construction of the present pump as shown in Figs. 1 to 3 resembles that disclosed in my Patent No. 1,263,663 of April 23, 1918, in that it comprises two single suction impellers 10 and 11 arranged back to back with their single suctions in opposite directions so as to balance the pump. The casing is also divided

5 on a horizontal plane into a lower section 12 and an upper section 13, bolted together,

each carrying a portion of the partition 14 which separates the impeller chambers. The lower section 12 carries the suction and discharge passages 15 and 16, respectively, with their connection ends. The driving shaft 9 is mounted between the two sections 12 and 13 with bearings in the partition 14 and in the casing wall.

Instead of the tangential delivery passage of gradually increasing cross sectional area which connects the first and second stages of the pump shown in the patent above mentioned, I now open the delivery volute 17 of the first stage directly downward into a large pressure chamber 18 formed in the foot of the pump. The volumetric capacity of the chamber is so great that the velocity of the water is reduced far below the velocity in the suction head of the pump. Opening at right angles from this chamber and below the volute 19 of the second stage of the pump is a narrow passage 20 through which the water passes with increased velocity. This passage develops into an upward lead 21 opening to the eye of the second impeller, and is of such varying cross sectional area that the velocity of the water is at first still further increased and then reduced again to that at the suction head of the first impeller. This has the effect of straightening out the eddies formed in the stream of water during its passage through the narrow irregular opening 20 beneath the second volute 19.

It will thus be seen that whereas in the pump of my prior patent the water passes from the first to the second stage with gradually decreasing velocity, in the present pump the flow of the water is varied and the velocity is first greatly decreased and then increased, and again decreased. These variations are all indicated in the diagram Fig. 4.

A pump of the present design is especially adapted to handle acidulous mine water, since in pumps for this purpose the speed of the water is kept as low as possible to minimize its corrosive action. By building the pressure chamber 18 of liberal proportions, the velocity of the water can be easily reduced, not only to an extent sufficient to prevent excessive corrosive action, but also to enable the current to make a sharp right angular turn without material friction loss. Furthermore, by forming the pressure chamber 18 in the foot of the pump the com-

plicated spiral passage of my Patent No. 1,263,663 is eliminated and the pattern and foundry work on the pump much simplified, as well as doing away with the unnecessary weight. This is an important point from the standpoint of economy, since a pump for handling acidulous waters must be built of acid resisting material such as bronze, the expense of which is high. Moreover, as it is customary to drive these pumps from an electric motor mounted on the same base plate as the pump, the motor standards are lower by reason of the lowered position of the shaft 9, and the weight of the installation is thus further decreased. The volutes are set about 90 degrees apart to produce the most efficient flow, and to best provide for the suction and discharge connections from the lower section of the casing.

In the modified construction shown in Figs. 5, 6 and 7 I have shown my invention applied to a three-stage pump. As here shown the volutes 22, 23 and 24 are detached and all face in the same direction. A balanced installation may be secured, however, by coupling a unit of the present type with another unit of like type in which the suction faces are oppositely faced.

The pump casing comprises three sections, 25, 26 and 27, the first two forming the pump body proper, while the section 27 comprises the pressure chamber connecting the several stages of the pump, the three sections being mounted upon a base plate 28. The suction pipe 29 is connected to the intake 30, opening to the eye of the impeller 31 in the volute 22 of the first stage of the pump. This volute discharges through a passage 32 to a pressure chamber 33 of great volumetric capacity and turns at right angles at relatively slow speed and high pressure downward to a passage 34 leading to the eye of the second stage impeller. The discharge from the second stage enters a second pressure chamber 35 separated from passage 34 by a partition 36, and is in like manner led to the intake passage 37 for the third stage from which the water is discharged through the pipe 38.

In both constructions the water passes from one stage to another of the pump through a pressure chamber of large capacity, in which the velocity of the current is low, and from which the water is discharged at a sharp angle to a passage leading the water at increased velocity to the succeeding stage of the pump.

In a pump of the three or more stage type shown in Figs. 5 to 7 the construction is such that the interiors of the pressure chambers may be lined with wood or cement to protect the walls of the chamber from the corrosive action of acidulous waters. Inasmuch as such a lining is readily formed,

due to the shape of the pressure chamber, it is possible to make this portion of the pump casing of cast iron—a great economy in construction.

Various modifications in detail will readily occur to those skilled in the art which do not depart from what I claim as my invention.

I claim:

1. A multi-stage centrifugal pump having, between successive stages, a pressure chamber of large capacity to which one stage delivers at relatively high velocity, and through which the fluid passes at relatively low velocity, a connecting passage 80 leading therefrom at a sharp angle and of such reduced cross sectional area that the fluid is caused to pass therethrough at increased velocity to the succeeding stage of the pump. 85

2. A multi-stage centrifugal pump having, between successive stages, a pressure chamber of large capacity to which one stage delivers at relatively high velocity, and through which the fluid passes at relatively low velocity, a connecting passage 90 leading therefrom at a sharp angle and of such reduced cross sectional area that the fluid is caused to pass therethrough at increased velocity to the succeeding stage of 95 the pump, said connecting passage delivering the fluid to the succeeding stage of the pump at substantially the same velocity as the suction of the preceding stage.

3. A multi-stage centrifugal pump having, between successive stages, a pressure chamber of large capacity to which one stage delivers at relatively high velocity, and through which the fluid passes at relatively low velocity, a connecting passage leading 105 therefrom at a sharp angle and of such reduced cross sectional area that the fluid is caused to pass therethrough at increased velocity to the succeeding stage of the pump, said connecting passage having a varying 110 cross sectional area to cause the fluid to pass from the pressure chamber at greatly increased velocity and then at reduced velocity at the point of delivery to the suction of the succeeding stage. 115

4. A multi-stage centrifugal pump having, between successive stages, a pressure chamber of large capacity to which one stage delivers at relatively high velocity, and through which the fluid passes at relatively low velocity, a connecting passage leading 120 therefrom at a sharp angle and of such reduced cross sectional area that the fluid is caused to pass therethrough at increased velocity to the succeeding stage of the pump, 125 said connecting passage having a varying cross sectional area to cause the fluid to pass from the pressure chamber at increased velocity, then at further accelerated velocity and finally at reduced velocity at the point 130

of delivery to the suction of the succeeding stage.

5. A multi-stage centrifugal pump having, between successive stages, a pressure chamber of large capacity to which one stage delivers at relatively high velocity, and through which the fluid passes at relatively low velocity, a connecting passage leading therefrom at a sharp angle and of 10 such reduced cross sectional area that the fluid is caused to pass therethrough at increased velocity to the succeeding stage of the pump, said connecting passage having a varying cross sectional area to cause the 15 fluid to pass from the pressure chamber at increased velocity, then at further accelerated velocity, and finally at reduced velocity at the point of delivery to the suction of the succeeding stage, the velocity at the 20 point of delivery to the succeeding stage corresponding substantially to the suction velocity of the preceding stage.

6. A centrifugal pump having two single suction impellers arranged back to back 25 with their single suctions in opposite directions and with volute deliveries, a pressure chamber of large capacity to which the first volute discharges, a passage of relatively 30 small cross sectional area opening at a sharp angle to said pressure chamber and leading the fluid at increased velocity to the eye of the second impeller.

7. A centrifugal pump having two single suction impellers arranged back to back 35 with their single suctions in opposite directions and with volute deliveries, a pressure

chamber of large capacity to which the first volute discharges, a passage of relatively small cross sectional area opening at a sharp angle to said pressure chamber and leading 40 the fluid at increased velocity beneath the volute of the second impeller and upward to the eye thereof.

8. A centrifugal pump having two single suction impellers arranged back to back 45 with their single suctions in opposite directions and with volute deliveries, a pressure chamber of large capacity formed in the foot of the pump casing, to which the first volute discharges, a passage of relatively 50 small cross sectional area opening at a sharp angle to said pressure chamber and leading the fluid at increased velocity to the eye of the second impeller.

9. A centrifugal pump having two single 55 suction impellers arranged back to back with their single suctions in opposite directions and with volute deliveries, a pressure chamber of large capacity to which the first volute discharges, a passage of varying cross 60 sectional area opening at a sharp angle to the pressure chamber and leading therefrom to the eye of the second impeller, the shape of such passage being such as to cause the fluid to pass from the pressure chamber at 65 increased velocity, which is reduced at the point of delivery to the second impeller to a velocity substantially corresponding to the suction velocity of the first impeller.

In testimony whereof I have signed my 70 name to this specification.

OTTO HAENTJENS.
